UNITED STATES PATENT OFFICE.

ALLAN M. BROWNE, OF PASCAGOULA, MISSISSIPPI, ASSIGNOR OF ONE-HALF TO McVEA YOUNG, OF PASCAGOULA, MISSISSIPPI.

MUSIC-HOLDER.

1,161,606.

Specification of Letters Patent.

Patented Nov. 23, 1915.

Application filed November 27, 1914. Serial No. 874,198.

To all whom it may concern:

Be it known that I, ALLAN M. BROWNE, a citizen of the United States, residing at Pascagoula, in the county of Jackson and 5 State of Mississippi, have invented certain new and useful Improvements in Music-Holders, of which the following is a specification.

This invention relates to an improvement 10 in music holders.

One of the principal objects of the invention is to provide a music holder adapted to be used as an envelop or port-folio for carrying sheets of music, and having means 15 for supporting the sheets against accidental displacement, in view of the musician while he is reading them.

Another object of the invention is to provide a device of the class described in the 20 form of a port-folio having a longitudinal aperture or slot normally covered by a strip of material to prevent accidental displacement of the sheets of music from the envelop through said slots, and having means 25 adjacent the slot adapted to co-act with the back of the envelop or with the sheets of music contained therein, in maintaining a sheet against accidental displacement, and in view of the musician.

30 Still a further object of the invention is to provide a device of the class described which will be extremely simple, durable, efficient in operation and inexpensive to manufacture.

35 With these and other objects in view which will become apparent as the description proceeds, the invention resides in the construction, combination and arrangement of parts, hereinafter more fully described 40 and claimed, and illustrated in the accompanying drawing, in which like characters of reference indicate like parts throughout the several figures, of which—

Figure 1 represents a perspective view of 45 a music holder constructed according to my invention. Fig. 2 represents a vertical transverse sectional view therethrough. Fig. 3 represents a fragmentary horizontal sectional view taken on the plane indicated by the line 3—3 of Fig. 1. Fig. 4 represents a vertical transverse sectional view taken through the holder showing the same in position for holding a sheet of music in view of the musician. Fig. 5 represents a hori-

zontal sectional view taken on the plane 55 indicated by the line 5—5 of Fig. 1.

In carrying out my invention I provide a port-folio or envelop consisting mainly of a front wall 5, a back wall 6 and end flaps or closures 7. The envelop or port-folio 60 may be made of any suitable material such as cardboard or prepared cloth. The front and rear walls may be formed integrally, and by bending a single piece of material upon itself or they may be made separately 65 and suitably hinged along one edge. The end flaps or closures 7 may also be formed of some suitable flexible material, and they extend from the upper edges of walls 5 and 6 to a point midway the width of the walls, 70 as indicated in Figs. 1 and 2. The end flaps are creased along their central longitudinal lines as at 8 so that when the envelop is collapsed they will fold inwardly upon the music contained in the envelop. A suitable 75 fastening device is provided and may consist of a flap 9 secured to one wall and carrying a socket 10 adapted to be engaged upon a ball 11 carried by the other wall, or some other suitable fastening means may be utilized.

Wall 5 is provided near the bottom of the envelop, that is near the line at which the walls are hinged together, with a longitudinal aperture or slot 12. A strip of wood or 85 metal or other suitable material, indicated at 13, is secured on the inside of wall 5 along the lower edge of slot 12, that is along the edge nearest the hinged connection between walls 5 and 6, the upper face of said strip 90 preferably lying flush with the lower edge of the slot. A flap or sheet of paper or other suitable flexible material, indicated at 14, is pasted or otherwise secured to the inside of wall 5 and at its lower portion overhangs slot 12 and strip 13 as indicated in Fig. 2. The lower end of sheet 14 is preferably free from and unattached to wall 5, but extends down to the line along which the walls are hinged together.

When sheets of music indicated at 15 are placed in the envelop in the manner indicated in Figs. 1 and 2, they will be prevented from slipping out of the same through the slot 12 by reason of the lower 105 portion of sheet 14 overhanging said slot in the manner indicated. In this way as many sheets as the capacity of the envelop will

allow may be carried from place to place. When the musician desires to set one or more of the sheets up for use, they may be abstracted from the envelop, and the latter 5 be turned upside down and placed upon a lyre 16 in the position shown in Fig. 4. The sheet being used, indicated at 18, is inserted at its upper end through the slot 12 and is passed beneath strip 13 between the same 10 and the free end of sheet 14, in the manner indicated in Fig. 4. The clip 17 of the lyre may be utilized to press the lower portion of the sheet against the envelop as indicated in Fig. 4. In this manner the sheet 15 is supported against accidental displacement such as might be caused by wind or breeze blowing against the sheet. In maintaining sheet 18 in position, the strip 13 co-acts with the rear wall 6, or with the sheets of 20 music still contained in the envelop, in pressing or binding the upper portion of sheet 18 between them, so that it may not readily become accidentally withdrawn from its position. The sheet 18 is also partially maintained in position by the fact that in being 25 passed between the strip 13 and free end of sheet 14, it follows along the latter into the apex of the envelop, or the line upon which the walls are hinged, thus becoming 30 tightened between the sheet and adjacent wall 5 of the envelop.

The front and rear walls may if desired be stiffened or reinforced in the manner indicated in Fig. 5 by means of strips 19 of 35 suitable flexible or stiffened material as may be desired. These strips may be secured in any suitable manner to the walls, such for instance as being inclosed by tape or adhesive material indicated at 20. The strip 40 13 as indicated, is substantially triangular shaped in cross section, so that an edge 21 may be presented for binding the music sheet in position when inserted beneath said strip.

45 Although I have described the preferred embodiment of my invention, I may desire to make such changes in the construction, combination and arrangement of parts thereof as do not depart from the spirit of 50 the invention and the scope of the appended claims.

I claim:—

1. A music holder comprising a front and rear wall hingedly connected together and 55 adapted to be maintained in closed position at will; flexible closure flaps connected to

said front and rear walls at the ends thereof, one of said walls being provided near the hinged point of the walls with a longitudinal slot, a strip of suitable material secured 60 on the inside of said one wall along the edge of the slot adjacent the hinged point, a sheet of flexible material secured to said one wall and having a loose portion overhanging said slot and strip, said strip being substantially 65 triangular in shape whereby to provide a binding edge adapted to maintain a sheet of music against accidental displacement when inserted between said strip and the opposite wall of the holder. 70

2. A music holder comprising a front and rear wall hingedly connected together and adapted to be maintained in closed position at will, one of said walls being provided adjacent the hinged point with a longitudinally disposed slot, a binding strip secured on the inside of said one wall along the edge of said slot adjacent the hinged point, and a sheet of flexible material secured to said one wall and overhanging said slot and 80 binding strip substantially as described. 75

3. A music holder comprising a pair of walls hingedly connected together and adapted to be maintained in closed position at will, one of said walls being provided 85 with an opening adjacent the hinged point, means overhanging said opening on the inside of said one wall to prevent loss of music sheets through the opening, and binding means secured adjacent the opening on the 90 inside of said one wall and adapted to coact with the opposite wall in binding a sheet of material in position between them, when inserted through the opening between the 95 overhanging means and binding means. 95

4. A device of the class described including an envelop adapted to contain sheets of music and adapted to be maintained in closed position at will, one wall of the envelop being provided with an opening, 100 means for preventing displacement of sheets of music from the envelop through the opening, and binder means adapted to co-act with another wall of the envelop in binding a sheet of music in position between them when inserted through said opening and between the binder means and first said means. 105
